Des. 186,994
Patented Jan. 5, 1960

186,994

CONTROL PANEL FOR KITCHEN SINK OR SIMILAR ARTICLE

Henry Dreyfuss, South Pasadena, Calif., assignor to
Crane Co., Chicago, Ill., a corporation of Illinois

Application August 7, 1958, Serial No. 52,097

Term of patent 14 years

(Cl. D49—1)

Fig. 1 is a perspective view of a control panel for kitchen sink embodying my new design; and

Fig. 2 is a top plan view thereof.

The letters and numerals shown in broken lines are for illustrative purposes only.

I claim:

The ornamental design for a control panel for kitchen sink or similar article, substantially as shown and described.
